UNITED STATES PATENT OFFICE.

JOHN O. NYMAN, OF CANTON, OHIO, ASSIGNOR TO THE CENTRAL METAL PRODUCTS COMPANY, OF CANTON, OHIO, A CORPORATION OF OHIO.

METAL DOOR.

Application filed August 1, 1921. Serial No. 488,761.

To all whom it may concern:

Be it known that I, JOHN O. NYMAN, a subject of the King of Sweden, residing at Canton, in the county of Stark and State of Ohio, have invented a new and useful Metal Door, of which the following is a specification.

This invention relates to metal doors and more particularly to a hollow, metal door 10 of the flush type, in which reinforcing means is provided upon the interior of the door.

The objects of the invention are to provide a hollow, metal door formed of spaced sheets of metal having their edge portions 15 connected together and having channel shaped, reinforcing members slidably inserted at spaced intervals between the sheets.

The above and ancillary objects may be attained by providing two similar sheets 20 with inturned flanges at their vertical edges, a connecting strip being spot welded or otherwise attached to said flanges, vertical strips being attached at spaced intervals upon the inner sides of the sheets and provided 25 with vertical grooves, channel shaped reinforcing ribs being provided with inturned flanges arranged to be inserted into said grooves, horizontally disposed channel members being spot welded or otherwise connected 30 within the upper and lower ends of the sheets and engaging said reinforcing ribs.

The invention thus set forth in general terms is illustrated in the accompanying 35 drawings, in which—

Figure 1 is a side elevation of a door embodying the invention, parts being broken away for the purpose of illustration;

Fig. 2, a section on the line II—II, Fig. 1; 40 Fig. 3, a similar section of a portion of the door upon an enlarged scale;

Fig. 4, a section on the line IV—IV, Fig. 3;

Fig. 5, a section on the line V—V, Fig. 3; 45 Fig. 6, a perspective view of a portion of one of the strips which is attached to the inner face of each sheet of the door; and

Fig. 7, a perspective view of a portion of one of the reinforcing ribs.

Similar numerals of reference indicate corresponding parts throughout the drawings.

The door is formed of two spaced sheets of metal indicated by the numerals 1 and 2, 55 each of which is of rectangular shape of

substantially the size of the finished door. An inturned flange 3 is formed upon each vertical edge of each of the sheets 1 and 2, the inner edges of the flanges upon opposite sheets engaging, as best shown in Fig. 3, the 60 sheets being connected together by means of the strips 4 which are of substantially the width of the two adjacent flanges 3 and are attached to the flanges 3 preferably by spot welding.

It will be evident that some reinforcement is necessary between the sheets 1 and 2 in order to strengthen the door and prevent the sheets from being bent or crushed together, and it will also be seen that any reinforcing 70 device located between the sheets would be an obstruction to the spot welding machine or tools by means of which the strips 4 are attached to the flanges 3.

In order to provide a suitable reinforcement for the interior of the door, which at the same time will not interfere with the operation of the spot welding machine or tools, the vertically disposed strips 5 are connected in oppositely disposed pairs at spaced 80 intervals upon the inner spaces of the sheets 1 and 2, as by spot welding, before the sheets are connected together.

Each of the strips 5 is provided with the vertical, channel portion 6, the inner edge 85 of which is spaced from the adjacent sheet as shown at 7. The reinforcing ribs 8 are of channel shape and are provided with the inturned flanges 9 at their edges.

After the strips 4 have been spot welded 90 to the flanges 3 of the sheets 1 and 2, these reinforcing ribs which are of slightly less length than the sheets 1 and 2 and which correspond in length with the strips 5, are then inserted as best shown in Fig. 3, the 95 flanges 9 thereof being inserted into the grooves formed in the vertical ribs 6 of said strips, the reinforcing ribs being slidably placed in position.

After the reinforcing ribs have all been 100 placed in position, channel members 10 are inserted between the sheets 1 and 2 at the upper and lower ends of the door in the manner best shown in Fig. 5, these channels being connected to the sheets 1 and 2 as by 105 spot welding. The ribs 8 are thus held against longitudinal movement within the door, preventing any movement thereof which might cause any disagreeable sound.

It will be evident from the above that 110

a sheet metal door of the flush type is thus provided which is light in weight and at the same time is sufficiently durable to withstand hard use. It will also be seen that 5 the door may be easily assembled, as the flanges 3 may be spot welded to the connecting strips 4 before the reinforcing ribs 8 are inserted, the entire interior of the door thus being open to permit the necessary tools 10 to be inserted for the spot welding.

I claim:

1. A metal door comprising a pair of spaced, metal sheets connected together at their longitudinal edges, longitudinally disposed reinforcing ribs slidably inserted between said sheets, and means for preventing longitudinal movement of the reinforcing ribs after they are inserted between the sheets.
- 15 2. A metal door comprising a pair of spaced, metal sheets connected together at their longitudinal edges and provided with longitudinal grooves upon their inner sides and reinforcing ribs slidably inserted into said grooves.
- 20 3. A metal door comprising a pair of spaced, metal sheets connected together at their longitudinal edges, vertically disposed, grooved strips connected to the inner faces 30 of said sheets and reinforcing ribs slidably inserted into the grooves in said strips.
- 35 4. A metal door comprising a pair of spaced, metal sheets connected together at their longitudinal edges, vertically disposed, grooved strips connected to the inner faces 40 of said sheets and reinforcing ribs slidably inserted into the grooves in said strips, and means at the end edges of the door for pre-

venting longitudinal movement of said ribs.

5. A metal door comprising a pair of 40 spaced, metal sheets connected together at their longitudinal edges, grooved, longitudinally disposed strips spot welded to the inner sides of said sheets, channel shaped ribs provided with longitudinal flanges arranged 45 to be slidably inserted into said grooves and transversely disposed channel members mounted within the upper and lower ends of the door and engaging said reinforcing ribs.

6. A metal door comprising a pair of spaced, metal sheets provided with inturned flanges at their longitudinal edges, a longitudinal connecting strip to which the inturned flanges at each side of the door 55 are spot welded, longitudinally disposed, grooved strips connected to the inner faces of the sheets and channel shaped, reinforcing ribs provided with flanges slidably inserted into said grooves.

7. A metal door comprising a pair of spaced, metal sheets provided with inturned flanges at their longitudinal edges, a longitudinal connecting strip to which the inturned flanges at each side of the door 65 are spot welded, longitudinally disposed, grooved strips connected to the inner faces of the sheets and channel shaped, reinforcing ribs provided with flanges slidably inserted into said grooves, and transversely 70 disposed, channel members connected within the end edges of the door and engaging the reinforcing ribs.

In testimony that I claim the above, I have hereunto subscribed my name.

JOHN O. NYMAN.
